BY

David O. Barnell

ATTORNEY

UNITED STATES PATENT OFFICE

LEWIS A. COCKLIN, OF GRISWOLD, IOWA

LIQUID FUEL BURNER

Application filed October 3, 1929. Serial No. 397,019.

My invention relates to oil or liquid fuel burners of the type wherein the liquid fuel is delivered to a porous filler or wick contained within an open-topped retort, the combustion of the fuel occurring at the top of said retort, and the heat from the zone of combustion serving to vaporize the liquid fuel in the upper portions of the filler or wick. It is the object of my invention to provide in a burner of this type means for limiting or inhibiting the transmission of heat from the zone of combustion of the fuel to the lower portion of the retort, whereby to maintain a zone of vaporization in the upper portions only of the filler or wick, and to enable the maintenance of a high temperature in the uppermost portions of the wick material, whereby to prevent or limit clogging of the wick by accumulation of solid carbonaceous residues from the vaporized fuel, and to facilitate the burning away of such non-volatile residues.

In the accompanying drawings, Fig. 1 is a vertical section through the retort of a liquid fuel burner constructed in accordance with my invention, and Fig. 2 is a bottom view of the annular baffle or extension-ring.

The burner illustrated in the drawings is of the general type wherein there is provided an annular retort having an outer wall 5 and an inner wall 6, the latter providing a tubular portion or air-flue through which is supplied most of the air required for combustion of the fuel. In the structure shown, the retort rests upon the upturned end portion of a horizontal tube or conduit 7, of which the opening in said upturned end portion is in register with the air-flue.

As installed for use, air is supplied to the conduit 7 by a suitable blower, or in some instances natural instead of forced draft may be employed, the usual arrangement for burners of this type being such that substantially all of the air supplied to the combustion-chamber of the furnace in which the burner is used enters said chamber through said conduit 7. At the upper end of the air-flue there is provided a removable cap or spreader 8 which is held in spaced relation to the upper end of the flue by means of shouldered lugs 9, the lower surface 10 of said spreader being

torically curved and adapted to direct air from the flue outwardly and slightly downward so as to impinge upon the upper surface of the wick or filler 11, with which the retort is filled to a level near the upper end of the air-flue. The wick or filler 11 comprises granular fragments of refractory mineral composition, of porous or spongy consistency, and having relatively low heat conductivity. A flat ring 12 is supported on fixed lugs 13 near the bottom of the retort, to provide an annular space or distributing channel 14 from which the filler material is excluded, and to which the liquid fuel is supplied through a suitable pipe 15. The ring 12 fits loosely within the retort, so that the fuel from the distributing channel may flow about the edges thereof, and rise into the filler 11 to a level determined by the fuel-control devices associated with the burner. The outer wall 16 of the retort, at a level slightly below the upper end of the air-flue, is shouldered outwardly to form a ledge, from which the marginal flange 16 extends up to a level above the top of the air-flue. Seated upon the shoulder or ledge within the flange 16 is the extension-ring 17, which has a plurality of lugs 18 fitting within the flange to center the ring therewith. Said lugs 18 are extended slightly below the lower edge of the ring 17 whereby to support the same slightly above the ledge, and to thus provide a small air-space between the ring and the wall of the retort. The inner side of the extension-ring at the lower part thereof is substantially in register with the inner side of the retort-wall, the upper portion of the ring is flared outwardly, and at the upper end of the ring an integral flange 19 extends out to the same diameter as that of the wall-flange 16.

In the operation of the burner, the gravitational level of the liquid fuel in the retort varies according to the rate at which the fuel is supplied thereto, and some of the liquid is carried above the gravitational level, or to the upper portion of the wick material, by the capillary action of said material, due to the porosity thereof above mentioned. After operation of the burner has been started by igniting the fuel at the top of the retort, the

upper portions of the wick material quickly become heated to a temperature such as to cause vaporization of the liquid as it approaches the upper surface, and the resulting gas or vapor rising from the wick becomes mixed with the air emerging from beneath the spreader 8. The impinging air-current, sweeping across the upper surface of the filler or wick material, carries the flame radially outward, and at the outer edge of the retort the flame is directed upwardly by the extension-ring 17. Said ring thus serves as a deflector or baffle to limit lateral spreading of the flame, and will become intensely heated. 10 The heat radiated inwardly from the ring tends to raise the temperature of the upper portions of the filler or wick material 11, to more effectively vaporize the oil in said upper portions, but by reason of the low conductivity of said material the heat from the upper portions is not transmitted to the lower portions of the material in sufficient amount to cause vaporization of the oil below the desired vaporizing zone. Some of the heat 20 from the ring 17 is transmitted to the outer wall of the retort, but the heating of said wall is limited by reason of the spaced relation of the ring thereto, the air-space between the parts serving as an insulator, and actual conduction of heat from the ring to the wall occurring only through the limited areas of contact afforded by the lugs 18. In burners of large size the extension-ring may be formed of non-metallic refractory material, but in 30 small burners it is found that the extension-ring may be of cast metal without causing the conduction of heat therefrom to the retort wall to become objectionably great. 35 It is desirable that the insulating air-space 40 between the extension-ring and the wall of the retort be close to or substantially at the level of the upper surface of the wick or filler 11, so that the wall of the retort will not be directly exposed to the flame at said surface. It is also desirable that should the flame of the burner become extinguished while the liquid fuel is being supplied to the retort, or should the fuel supply be turned on without igniting the burner, or if an excessive quantity of fuel be supplied to the retort at any time, so that the liquid level in the retort would rise to the top thereof, the excess of liquid may flow over the upper end 50 of the flue 6, passing down through said flue to the conduit 7, rather than to overflow the outer wall of the retort. These desirable results are attained by the extension of the outer flange 16 to a level above the upper end 55 of the flue 6, so that while said flue extends above the surface of the filler 11, and the latter extends to the level of the shoulder or ledge on which the extension-ring rests, no overflow can occur except at the inner 60 wall or air-flue. 65

Now, having described my invention, what I claim and desire to secure by Letters Patent is:

1. In a liquid fuel burner, a retort having an annular chamber open at the top, the inner wall of said annular chamber forming a vertical air-passage, spreading means at the upper end of said air-passage for directing the air therefrom outwardly across the top of the annular chamber, a filler of porous granular refractory material of low heat conductivity filling said annular chamber, means for supplying liquid fuel to the lower portion of the annular chamber, and means insulated from the outer wall of the retort and extending above the filler material peripherally of the annular chamber to baffle laterally and direct upwardly the flame from the surface of the filler. 70 75

2. In a liquid fuel burner, the combination with an open-topped retort having a central air-passage, porous refractory material filling said retort, means for supplying liquid fuel to the lower portion of the retort, and means for directing air from the central passage outwardly across the surface of the filling material, of an annular baffle-member arranged peripherally of the retort above the surface of the filling material, and means for limiting conduction of heat from said baffle-member to the wall of the retort. 80 90

3. In an oil burner, the combination with an annular retort having a central air-flue and a shouldered outer wall forming a ledge at a level slightly below the upper end of the air-flue, porous granular refractory material filling said retort substantially to the level of said ledge, a spreader disposed over the upper end of said air-flue and adapted to direct the air therefrom outwardly across the surface of the filling material, and means for supplying oil to the lower portion of said retort, of a ring disposed above said ledge and forming an upward extension of the retort wall, said ring being spaced from said wall to limit conduction of heat from the ring to the wall. 100 105

4. In a liquid fuel burner, the combination with a retort having an annular chamber open at the top, the inner wall of said annular chamber forming an air-flue and the outer wall of said annular chamber being shouldered outwardly to form a ledge at a level below the top of said air-flue, a filler of porous granular material filling said annular chamber to substantially the level of said ledge, means for supplying liquid fuel to the lower portion of said annular chamber, and means for directing air from the top of said air-flue outwardly across the surface of said filler, of a marginal flange formed integrally with said outer wall of the retort and extending upwardly from said ledge to a level above the top of the air-flue, and a 110 115 120 125 130

ring disposed above said ledge within said marginal flange, said ring having lugs engaging said marginal flange to center the ring therewith, said lugs also engaging the ledge to space the ring therefrom, whereby to limit conduction of heat from the ring to the wall of the retort.
